H. W. McCULLOCH.
BRAKE BAND,
APPLICATION FILED SEPT. 15, 1919.

1,371,917.

Patented Mar. 15, 1921.

FIG. 2.

FIG. 1.

FIG. 3.

INVENTOR
Harold Weed McCulloch

BY his ATTY

W. Way Emerson

UNITED STATES PATENT OFFICE.

HAROLD WEED McCULLOCH, OF NEW YORK, N. Y.

BRAKE-BAND.

1,871,917.

Specification of Letters Patent. Patented Mar. 15, 1932.

Application filed September 15, 1919. Serial No. 822,727.

To all whom it may concern:

Be it known that I, HAROLD WEED McCULLOCH, a citizen of the United States, residing at the city of New York, county of Bronx, and State of New York, have invented new and useful Improvements in Brake-Bands, of which the following is a specification.

My invention relates to brake bands or more particularly to devices of the class described which have removable lining members and has for an object to provide a band that may be readily drawn and replaced without unduly dismantling associated parts.

Another object of my invention is to provide a band having interchangeable sections any one or all of which can be replaced when worn or damaged without necessitating the substitution of the entire band.

Other objects and advantages will appear in the specification and claims hereinafter contained.

My improved band may be applied to and used with any brake drum structure but its greatest advantage will appear when employed in connection with a drum inclosed in a casing which must be removed in whole or in part, to render accessible the contained mechanism, as, for example, in the familiar Ford automobile where the planetary transmission mechanism comprises a plurality of drums each with a separately actuated brake band all inclosed within a case having two members bolted together one over the other.

In opening up the case, that is in lifting off the upper half it is ordinarily necessary not only to remove all the bolts of the casing itself, but to disconnect and remove many adjacent parts, all of which makes the operation a laborious and therefore expensive undertaking.

Referring again to the so-called Ford construction, there is at the extreme top of the transmission casing an opening of a relatively reduced area over which there is a cover especially designed for relatively prompt removal, and this serves to expose to a limited extent the interior mechanism.

In applying my improvement to such construction each band within the transmission case can be removed through the relatively small opening at the top and the parts repaired or the band refined and replaced around the respective drums by insertion therethrough.

Therefore, described in general terms, my

improved band comprises a plurality of sections, preferably three, namely, the principal or under side of the band and two top portions to which the lips or clamping lugs are attached at the head. The lower member is of semicircular form, suitably shaped relatively to the drum and of a size slightly greater in circumferential length than would be required to cover one half of the drum to which it applies.

Two similar top sections are adapted to the respective ends of the first mentioned section and overlapping those portions are secured thereto.

The overlap portions of the top pieces are offset to the extent of the thickness of the band section to which they relate, so as to form recesses to receive the respective ends of the sections and are attached by means of the transverse slots through which the nose of a hook enters from the main section and a machine screw or rivet is added to firmly secure the two portions together.

Upon the two top sections are secured in the usual way the clamping forks or lugs by means of which the ends of the band as a whole may be drawn together to coact with the brake drum to which it relates.

The accompanying drawings illustrate a preferred embodiment of my invention, and are made a part of this specification, of which—

Figure 1 is a side view of an assembled band upon a drum with position of inclosing casing indicated by broken lines.

Fig. 2 is a side elevation of the band as shown in Fig. 1.

Fig. 3 is a sectional view on lines 3—3 of Fig. 2.

Referring to the drawings, the numeral 1 represents the band as a whole which has the two lugs 2 and 3 secured thereto in any convenient manner as by screws or rivets, but in the preferred form of my invention I have these members secured in a manner that is more conducive to readily detaching them from the mechanism to which they pertain.

This last mentioned object is attained in the present form of my invention by means of a hooked tongue 4 projecting from the outer surface of each of the members 10 and entering a slotted opening 5 suitably disposed in the shoulder portion of each of the lugs, the tongue piece 4 thus acting as a catch and when the lug is drawn firmly against the hooked member, the latter being

suitably curved or tapered on its under side, the contact between the parts is thus made close and secure.

When the foot of the lug is thus brought 5 into a snug fit upon its supporting member

10 a screw or rivet, preferably the screw 6, is threaded into the supporting member after having been passed through the shoulder portion of the lug (as best shown in Fig. 10 3) and thereby renders permanent the union of these parts.

The two sectional band members 10 to which the lugs are attached in the manner described, and the main sectional member 15 20 to which they are united in a manner next to be described, together form the peripheral brake band of the preferred form of my invention. The main section 20, as already pointed out, has been designed to 20 extend circumferentially to cover slightly more than one half the drum periphery 30 to which it applies so that it may be sprung on and off the body of the drum with greater facility.

25 In the form illustrated in the drawings the band sections 10 are united to the main section 20 by means of the hook and screw devices already described whereby the lugs 2 and 3 are attached to the first mentioned 30 sections, and to this end the said sections 10 while conforming to the curvature of the drum to which the band applies, are offset at their medial transverse line to the extent of the thickness of the main section 20, the 35 portion of the smaller diameter containing a hook 4 and the threaded orifice for receiving the screw 6, similar to the devices by means of which the lugs 2 and 3 are attached as described.

40 Accordingly upon the respective ends of the member 20 are provided the similarly disposed outwardly projecting hooked catches 4 adapted to enter the slotted openings 5 which are in the portion of the larger 45 diameter of the respective section 10 and the screws 6 and make permanent the connections between the band sections substantially in the same manner as that described for securing the lugs to the first mentioned 50 band sections.

While I have described somewhat fully the features illustrated as a preferred form of the means for uniting the lugs to the band sections, as also regarding the connecting means between sections of the band proper, it is however not desired to limit my invention to the particular means thus specifically described. My improvement is designed broadly to provide a sectional band 60 that possesses all the advantages of a single band but having means for disconnecting its parts as occasion arises.

In employing my improved band it may be assembled completely as shown in Figs. 65 1 and 2 and applied to the drum in the

usual manner and if any section becomes worn or injured it will be replaced by taking out the screws 6 and unhooking the parts affected, replacing the section to be restored.

70 But if it be found necessary to place the band upon a drum partially inclosed in a casing, such as the Ford transmission case as hereinabove referred to, the parts would be disconnected preparatory to their insertion and the section 20 with the full strip of lining riveted thereto is inserted longitudinally through the smaller opening at the top of the casing and in this manner forced around the drum until the forward end of 75 the lining appears at the upper surface of the drum.

The usual brake lining is securely riveted midway of its length to the sectional member 20 as it has been found necessary only 80 to secure to the respective sections 10 the extreme ends of the lining. Hence, in proceeding with the inserting of the band through the narrow opening as above the section 10 before having the lug attached thereto is then attached to the end of the band section 20 by having the hook 4 thereon passed through the square opening 5 and completing the union by inserting the screw 6. Thereupon the second section is added 95 in like manner, the band being properly shifted longitudinally upon the drum successively to expose the unconnected portions in the order required as indicated.

After the sections 10 and 20 have been 100 articulated the lugs 2 and 3 are thereupon attached one after the other in practically the same manner as the sections 10 were put on the main band section, and then the respective ends of the strips of lining are 105 brought around the respective lugs and secured by a screw as best shown in Fig. 1.

Having described my invention, what I claim is:

1. A brake band having a major section, 110 two minor sections detachably connected to the ends of the major section, a lining element carried by the major section, and detachable means for securing the free ends of the lining to the free ends of the minor 115 sections.

2. A brake band having a major section, two minor sections detachably connected to the ends of the major section and forming therewith a substantially continuous inner 120 bearing surface, operating lugs detachably carried by the major section, and detachable means for securing the free ends of the lining to the free ends of the minor sections.

3. A brake band having a major section, 125 two minor sections detachably connected to the ends of the major section, operating lugs detachably secured to the free ends of the minor sections, a lining element carried by the major section, and detachable means for 130

securing the free ends of the lining to the free ends of the minor sections.

4. A brake band having articulated sections whose ends overlap and means for securing said overlapping ends together, said means comprising a hook in one of said sections and a slotted opening in the overlapping end of the other of said sections.

5. A brake band having articulated sections whose ends overlap and means for securing said overlapping ends together, said means comprising a hook in one of said sec-

tions, a slotted opening in the overlapping end of the other of said sections, and screws securing said overlapping parts together.

6. A brake band adapted to be used on a drum, said band having readily separable steel band sections, an inner lining of suitable material, permanently attached to one of said sections and detachably secured at its ends to two of said sections.

In testimony whereof I have hereunto set my hand.

HAROLD WEED McCULLOCH.
